UNITED STATES PATENT OFFICE.

ISAAC DUECK PLETT, OF STEINBACH, MANITOBA, CANADA

POCKET-HOLDER.

1,083,942.

Specification of Letters Patent. Patented Jan. 13, 1914.

Application filed December 12, 1912. Serial No. 736,370.

To all whom it may concern:

Be it known that I, ISAAC DUECK PLETT, of the village of Steinbach, in the Province of Manitoba, Canada, have invented certain new and useful Improvements in Pocket-Holders, of which the following is the specification.

The invention relates to a pocket holder and the object of the invention is to provide an inexpensive holder which can be inserted within a pocket holding the top of the pocket open and the bottom flat so that any article can be readily inserted in the pocket and when once in will be held from accidental displacement therefrom.

With the above object in view the invention consists essentially in a single strand of wire bent centrally more or less in a U-shape and having the ends thereof coiled the arrangement and construction being hereinafter more particularly described.

Figure 1 is a perspective view of the device as it appears when in use in a pocket. Fig. 2 is an enlarged detailed vertical sectional view through a pocket supplied with my device. Fig. 3 is an enlarged detailed perspective view of the ends of the wire.

In the drawing like characters of reference indicate corresponding parts in each figure.

The device as disclosed is particularly useful for holding rules and such like articles used by a carpenter in the pocket of overalls worn by him.

Referring to the drawing:—1 represents a pair of overalls supplied with the more or less narrow pocket 2 for the reception of such articles as a rule 3.

4 represents my holder which is formed from a single strand of spring wire bent more or less in a U-shape the body 5 of the wire being straight to conform with the bottom of the pocket, the extending ends of the wire 6 and 7 being slightly bowed while the extremities are coiled at 8 and 9. Each extremity is formed with two coils the second coil being somewhat higher than the first coil and terminating at the front or forward side of the first coil. The wire immediately

beneath the coil in each instance is straight 50 up and down between the points, 10 11, 10' and 11' and then bowed outwardly the bows terminating at the cross or body piece 5. It is to be noticed that the coils are formed on the outer side of the upturned ends of 55 the wire.

The device is inserted in the pocket with the body piece bearing on the bottom of the pocket and the coils located at the top of the pocket. The cloth or such material forming 60 the pocket is inserted in each instance between the end of the second coil and the adjoining face of the first coil away from the first coil and allowing it to take its original position after the cloth has been pulled partially over the first coil. The bowed parts 6 and 7 of the inserted wire spread the bottom portion of the pocket so that it lies flat or is tightly stretched while the coils hold the upper end of the pocket open.

With this device applied in a pocket a ruler or such like can be quickly inserted in the pocket through the open top and it will be held against accidental displacement by the tightly stretched lower portion of 75 said pocket it being understood of course that the rule is shoved well into the pocket.

What I claim as my invention is:—

A safety attachment for pockets comprising a single strand of wire bent more or less 80 in U-shape form having a more or less straight body portion resting in the bottom of the pocket, outwardly bowed end portions passing upwardly from the body portion and adapted to spread the sides of the bottom portion of the pocket holding it flat 85 and a pair of coils located at the extremities of the end portions the coils of each pair receiving between them the upper edge of the pocket thereby holding the top of the 90 pocket open, as and for the purpose specified.

Signed at Winnipeg this 20th day of November 1912.

ISAAC DUECK PLETT.
